UNITED STATES PATENT OFFICE.

WILLIAM E. FITCH, OF SYRACUSE, NEW YORK, ASSIGNOR TO FRANK C. HOWLETT AND SARAH H. FITCH, BOTH OF SAME PLACE.

WATER OR AIR PILLOW.

SPECIFICATION forming part of Letters Patent No. 283,767, dated August 28, 1883.

Application filed January 17, 1883. (No model.)

To all whom it may concern:

Be it known that I, WILLIAM E. FITCH, of Syracuse, Onondaga county, New York, have invented as a new article of manufacture a new and Improved Water or Air Pillow, of which the following is a specification, reference being had to the accompanying drawings, in which—

Figure 1 is a plan perspective, and Fig. 2 a 10 like view with a hose attachment.

The object of my invention is to create an article which, by simple changes, can be adapted to and used for a variety of purposes.

It consists of a water or air pillow constructed with screw-stoppers inserted in both ends, one within a funnel integral with the body of the pillow and the other simply inserted in the end of the pillow, to which a nipple and hose or rubber tubing can be readily 20 attached or connected in order to adapt the pillow to other purposes.

It is constructed as follows:

A is the body, constructed of any shape or material desired, and usually having at one 25 end a funnel extending out beyond the body, within which a screw plug or stopper, B, is secured in the ordinary way, and at the other end a screw-cap stopper, C, secured to the body in the ordinary manner.

30 The stopper B is constructed of about the shape shown in the drawings, and has two parts, one of which is attached to the body, the head-piece screwing into the other.

The stopper C consists of a base-piece attached to the body and projecting outward far enough to permit a cap-piece to be screwed on over it, or to receive a nipple of such construction as to receive and hold a rubber tubing, D. E is a handle.

The pillow can be inflated with air by connecting any ordinary inflating device to one end. It can be filled with water by opening one of the plugs, usually the one within the funnel, and after filling closing it again. When the tubing D is attached, it can be filled through 45 the stopper B with any liquid desired, suspended by the handle, and, the stopper B being left open for a vent, the device becomes a reservoir for a self-acting fountain-syringe.

I am aware that a water-bed has been constructed in sections communicating with each other and provided with induction and education pipes for maintaining a circulation of water therethrough, and do not claim such as of my invention. 55

What I claim as my invention is—

1. As an article of manufacture, a water or air pillow consisting of a body, A, forming a single compartment, and having an opening adapted to receive a stopper, and means for suspending the pillow, located at one end, and at the opposite end having means for connecting a discharge-pipe, or for the insertion or application of a stopper, substantially as specified. 60

2. The water-bag A, provided with the stopper B and handle E at its top, and with the stopper C at its bottom, substantially as and for the purpose set forth. 65

In witness whereof I have hereunto set my hand this 6th day of January, 1883. 70

WILLIAM E. FITCH.

In presence of—

C. W. SMITH,
THOS. T. BREWSTER.
